MAHLON L. DUNBAR, OF NORWALK, OHIO.

INTENSIFIER FOR SPARK-PLUGS.

1,366,251.

Specification of Letters Patent. Patented Jan. 18, 1921.

Application filed November 24, 1919. Serial No. 340,246.

To all whom it may concern:

Be it known that I, MAHLON L. DUNBAR, a citizen of the United States, residing at Norwalk, in the county of Huron and State of Ohio, have invented new and useful Improvements in Intensifiers for Spark-Plugs, of which the following is a specification.

The object of my present invention is to provide an intensifier for spark plugs, of 10 simple, compact and durable construction, and one in which provision is made for adequately protecting the transparent sleeve against changes in temperature and extraneous blows without detracting in any measure 15 from the efficiency of the device.

To the attainment of said object the invention consists in the peculiar and advantageous intensifier hereinafter described and definitely claimed.

20 In the accompanying drawings, hereby made a part hereof:

Figure 1 is a side elevation, and Fig. 2 a plan view of my novel intensifier.

Fig. 3 shows the same partly in diametrical section.

Fig. 4 is an end elevation.

Fig. 5 is a transverse section taken in the plane indicated by the line 5—5 of Fig. 3, with the intermediate electrode in elevation.

30 Similar numerals of reference designate corresponding parts in all of the views of the drawings.

Among other elements my novel intensifier comprises an intermediate electrode 1, preferably rod-like as shown, and end electrodes 2 in the form of screws and susceptible of being uniformly adjusted toward and from the electrode 1 as occasion demands.

40 Each electrode 2 is kerfed at its outer end for the application of a screw-driver, or other adjusting device, and each bears a spring washer 3, a lock-nut 4 and a binding nut 5. One electrode 2 is also, by preference, equipped with an angular coupling member 6, the inner arm of which is mounted on the electrode and interposed between the nuts 4 and 5 thereof, and the outer arm adapted to be mounted and secured on the 50 exterior electrode of a spark plug. When deemed expedient a spring washer 3^a may be mounted on the last-named electrode 2 between the nuts 4 and 5, as shown.

The electrodes 2 are threaded into a dielectric housing 7 in which is a diametrical bore 8 and which carries the intermediate elec-

trode 1, arranged in intersecting relation to the bore 8, Figs. 3 and 5.

Surrounding the housing 7 is a transparent sleeve 9, preferably of glass, which is of less length than the housing in about the proportion illustrated, and at the ends of the said sleeve 9 are annular yielding members or gaskets 10, preferably of rubber. These annular members or gaskets 10 are interposed between the ends of the sleeve 9 and heads 11, preferably of metal, which are loose on the electrodes 2 and are flanged as indicated by 12, so as to surround and protect the end portions of the sleeve 9 and the 70 gaskets 10 as well as the joints between the sleeve and gaskets.

It will be apparent from the foregoing that notwithstanding the simplicity and compactness of my improved device, the 75 same is calculated to effectively intensify the spark of a plug to which it is applied; also, that while the gap in the intensifier is visible through the transparent sleeve 9 and the bore 8 in the dielectric housing 7, air 80 is effectually excluded from the gap and at the same time free expansion and contraction of the transparent sleeve 9 is permitted, with the result that the liability of the said sleeve being fractured while in use is 85 reduced to a minimum.

Having described my invention, what I claim and desire to secure by Letters Patent, is:

An intensifier comprising a dielectric 90 housing of even exterior diameter throughout its length and provided with a central diametrical bore, an intermediate diametrical electrode disposed in said housing at right-angles to and intersecting said bore, 95 longitudinal central end electrodes threaded in said housing and having their inner ends disposed in said bore opposite the intermediate electrode, a transparent sleeve, of less length than the housing, surrounding the 100 same; heads secured on the end electrodes and against the ends of the housing and having flanges reaching inwardly beyond the ends of the transparent sleeve, and gaskets surrounding the end portions of the housing and arranged in the heads and interposed between the ends of the transparent sleeve and the heads.

In testimony whereof I affix my signature.

MAHLON L. DUNBAR.
